CLAIM

The ornamental design for a manual handling system for glass laboratory bottles, as shown and described.

DESCRIPTION

FIG. 1 is a left side elevation view of a first embodiment of a manual handling device for glass laboratory bottles;

FIG. 2 is a top plan view thereof;

FIG. 3 is a top-right-front perspective view thereof;

FIG. 4 is a front elevation view thereof;

FIG. 5 is a right side elevation view thereof;

FIG. 6 is a rear elevation view thereof;

FIG. 7 is a bottom plan view thereof;

FIG. 8 is a left side elevation view of a second embodiment of a manual handling device for glass laboratory bottles;

FIG. 9 is a top plan view thereof;

FIG. 10 is a top-right-front perspective view thereof;

FIG. 11 is a front elevation view thereof;

FIG. 12 is a right side elevation view thereof;

FIG. 13 is a rear elevation view thereof; and,

FIG. 14 is a bottom plan view thereof.

The broken lines in the figures depict portions of the manual handling device for glass laboratory bottles that form no part of the claimed design.
